MEANS FOR PACKAGING HOSIERY FORMS

Filed May 21, 1929

Inventor
W. J. De Witt
By Roberts, Cushman & Walker,
Attorneys.

UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

MEANS FOR PACKAGING HOSIERY FORMS

Application filed May 21, 1929. Serial No. 364,797.

This invention relates to an improvement in means for packaging hosiery forms and other articles of an angular conformation. Hosiery forms, such as are shown, for instance, in my copending application, Serial No. 290,252, filed July 3, 1928, are not only angular in conformation but have a weight in the toe thereof. In the packaging of these forms it has been found difficult to ⁵⁵ 10 secure them snugly in position, so that they will not shift therefrom under the vibrations to which they are subjected during shipment and be scratched or damaged thereby.

15 The primary object of this invention is to provide means for so packaging such articles that they will not during shipment shift out of their desired position or come in contact with each other. ⁶⁰ 20 Other objects will appear from a consideration of the following specification taken in connection with the drawings which form a part thereof, and in which.

Fig. 1 is a plan view of a pair of hosiery forms mounted in a box or shipping case in accordance with this invention; ²⁵

Fig. 2 is a front elevation of one of the hosiery forms, illustrating the manner in which the toe of such forms is accommodated; and ³⁰

Fig. 3 is an enlarged sectional view, taken along the line 3—3 of Fig. 2.

In the drawings, the reference numeral 10 designates a shipping box or case having a ³⁵ central chamber 11 in which the articles are packed. In the chamber 11 along each side wall are removably inserted filler members 12 of rectangular conformation and along each end wall between the members 12 are

⁴⁰ 45 similar filler members 13. The walls of the chamber are thus lined with filler members preferably, though not necessarily, of corrugated material. Each filler member 13 is hollow, as shown in Fig. 3, and the inner wall ⁵⁰ 55 60 65 70 75 80 85 90 95 100

14 is slotted at one end to provide an opening into the interior of the filler member and an integral flap 15.

The toe 16 of each form 17 is inserted through the opening in the filler member 13, ⁵⁰ the flap 15 lying against the instep 18 of the

form as shown in Fig. 2. The forms 17 with the filler members are then placed in the chamber 11 with the upper end of each form resting against the unslotted portion of the inner wall 14 of the filler member 13 receiving the toe of the other form. The length of the chamber 11 is such that, when so inserted, the outer walls of the filler members 13 will rest against the end walls. Thus any tendency of the forms to shift longitudinally is ⁵⁵ ⁶⁰ prevented.

The flaps 15 separate the forms and the openings in the walls 14 are of the proper depth so that when the instep 18 on the form contacts with the base of the flap 15 the heel ⁶⁵ 19 is at the end of the filler member. The filler members 12 are then located in the chamber 11 to position the filler members 13 and close the ends thereof and to bear against the back of the forms 17 thus holding them ⁷⁰ against vibration laterally.

The filler members 13 are preferably formed with one wall 20 of double thickness, which wall, as shown in Fig. 2, is adjacent the wall 14 so that when the forms are packed the toes rest upon a double wall 20. ⁷⁵

It will thus be noted that the members 13 engage both the feet and the uppers of the forms and secure them in position. The unslotted portion of each member 13 forms a ⁸⁰ loop 22 which surrounds the weighted toe of a form and counteracts any tendency of the form to rotate. The filler members 12 prevent the toes from becoming disengaged from the loops. While suitable packing might be ⁸⁵ inserted between the forms to keep them apart it has been found of advantage to provide the flaps 15 and such construction is preferred.

It will be understood that the forms are ⁹⁰ usually wrapped individually and that additional packaging is provided so that, when the lids 21 of the case are folded over and sealed, the forms and filler members are held against shifting vertically. The wrapping ⁹⁵ and packing material are omitted from the drawings because, since such material forms no part of this invention, its inclusion would interfere with the clarity thereof.

The particular hosiery forms selected for ¹⁰⁰

illustration of this invention are what is known as "calf high" but it will be understood that forms of other heights such as "ankle high", "knee high" and "thigh high" are similarly packaged according to my invention and that other modifications of my invention may be made without departing from the spirit and scope thereof as set forth in the following claims.

10. I claim:

1. Means for packaging a pair of hosiery forms in the chamber of a case, comprising members having loops which receive the toes of the forms and walls between which the feet of the forms are inserted whereby the members counteract any tendency of the forms to rotate within the chamber.

2. Means for packaging a pair of hosiery forms in the chamber of a case, comprising members having loops which receive the toes of the forms, and against which the insteps rest, and walls between which the feet of the forms are inserted, whereby the loops counteract any tendency of the forms to rotate within the chamber and means preventing the toes from becoming disengaged from the loops.

3. Means for packaging a pair of hosiery forms in the chamber of a case, comprising a hollow filler member at each end of such case having an opening in the inner wall thereof through which opening the toe of a form is inserted, the upper end of each form resting against the inner wall of the filler member into the opening of which the toe of the other form of the pair is inserted.

4. Means for packaging a pair of hosiery forms in the chamber of a case, comprising a hollow filler member at each end of such case having an opening in the inner wall thereof through which opening the toe of a form is inserted, and an integral flap which rests against the instep of the form, the upper end of each form resting against the inner wall of the filler member into which the toe of the other form of the pair is inserted and being spaced from that form by said flaps.

5. Means for packaging a pair of hosiery forms in the chamber of a case, comprising a hollow filler member at each end of such case having an opening in the inner wall thereof through which opening the toe of a form is inserted, the instep of the form being at the inner edge of the opening, the heel of the form at the outer edge thereof and the upper end of the form resting against the inner wall of the filler member into which the toe of the other form of the pair is inserted, and means in the chamber holding the forms in position relative to the filler members.

6. Means for packaging a pair of hosiery forms in the chamber of a case, comprising a hollow filler member at each end of such case having an opening in the inner wall thereof through which opening the toe of a

form is inserted, the instep of the form being at the inner edge of the opening, the heel of the form at the outer edge thereof, and the upper end of the form resting against the inner wall of the filler member into which the toe of the other form of the pair is inserted, an integral flap projecting from each filler member and separating the forms, and means in the chamber holding the forms in position relative to the filler members.

7. Means for packaging pairs of hosiery forms in the chamber of a case, comprising a hollow filler member at each end of such case and spaced from the sides thereof having an opening in the inner wall thereof through which opening the toe of a form is inserted, the upper end of each form resting against the inner wall of the filler member into which the toe of the other form of the pair is inserted, and means at the sides of the case filling the spaces between the ends of the filler members and the side walls thereof.

8. Means for packaging pairs of hosiery forms in the chamber of a case, comprising a hollow filler member at each end of such case and spaced from the sides thereof having an opening in the inner wall thereof through which opening the toe of a form is inserted, and an integral flap which rests against the instep of the form, the upper end of each form resting against the inner wall of the filler member into which the toe of the other form of the pair is inserted and being spaced from that form by said flaps and means at the sides of the case filling the spaces between the ends of the filler members and the side walls thereof.

9. Means for packaging pairs of hosiery forms in the chamber of a case, comprising a hollow filler member at each end of such case and spaced from the sides thereof having an opening in the inner wall thereof through which opening the toe of a form is inserted, the instep thereof resting against one edge of the opening and the heel being at the opposite edge thereof, the upper end of each form resting against the inner wall of the filler member into which the toe of the other form of the pair is inserted and means at the sides of the case filling the spaces between the ends of the filler members and the side walls thereof and holding the forms in position relative to the filler members.

10. Means for packaging a hosiery form in the chamber of a case, including a hollow filler member having an opening in one wall thereof through which opening the toe of a form is inserted, said filler member including a loop which receives the toe of the form and against the edge of which the instep of the form rests.

11. Means for packaging a hosiery form in the chamber of a case, including a hollow filler member having an opening in one wall thereof through which opening the toe of a

form is inserted and from which opening extends a flap which normally rests against the form.

Signed by me at Auburn, New York, this

5 17th day of May, 1929.
